UNITED STATES PATENT OFFICE.

MIZELL BENJAMIN WARD, OF MARSHALL, TEXAS, ASSIGNOR OF ONE-FOURTH TO
CORNELIUS G. LANCASTER, OF MARSHALL, TEXAS.

TYPE-WRITER ATTACHMENT.

1,194,579.

Specification of Letters Patent. Patented Aug. 15, 1916.

Application filed February 9, 1915. Serial No. 7,024.

To all whom it may concern:

Be it known that I, MIZELL B. WARD, a citizen of the United States, residing at Marshall, in the county of Harrison and State of Texas, have invented a new and useful Type-Writer Attachment, of which the following is a specification.

The device forming the subject matter of this application is adapted to be employed primarily for shifting the carriage of a typewriter by foot or leg action, thus avoiding the necessity of removing the hand from the keys of the typewriter to effect a shifting of the carriage at the end of the line.

15 The invention aims to provide novel means whereby a typewriter carriage may be shifted as aforesaid, the construction being such that the carriage may be stopped at any desired point.

20 Another object of the invention is to provide novel means whereby the key shift levers of a typewriter, the movable tabulating element and the back spacing member may be operated.

25 It is within the scope of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawings:—Figure 1 shows the invention in front elevation, parts being broken away; Fig. 2 is an end elevation, parts being removed; Fig. 3 is a fragmental horizontal section showing in plan the actuating pedals and parts immediately connected therewith; Fig. 4 is a transverse section taken through that portion of the invention appearing in Fig. 3; Fig. 5 is a side elevation showing the clutch; Fig. 6 is a fragmental section showing a portion of the clutch; Fig. 7 is a transverse section showing the upper end of one portion of the clutch mechanism; Fig. 8 is a fragmental vertical section disclosing a portion of the mechanism whereby the capital and figure shift keys are actuated; Fig. 9 is a rear eleva-

tion showing an attachment employed when the device herein disclosed is used on an Oliver typewriter; Fig. 10 is an elevation of the arm forming a part of the structure shown in Fig. 9, parts being broken away; Fig. 11 is a fragmental section showing a modified form of the structure depicted in Fig. 9; Fig. 12 is a section on the line 12—12 of Fig. 11; Fig. 13 is a top plan showing a portion of the bracket which constitutes a part of the clutch mechanism.

The invention contemplates the use of a supporting structure which may be of any desired form. In the present instance and by way of illustration, the supporting structure is depicted as comprising forward legs 1 and rear legs 2. The legs 1 and 2 are united by lower side braces 3, and extended between the side braces 3 is a pedal support 4. Upper side braces 5 unite the legs 1 and 2. The forward legs 1 and the legs 2 are united by front and rear top bars 6. Supported on the bars 6 or otherwise upheld is a table 7. If desired, the supporting structure may embody upright standards 8 carrying a copy holder 9.

Mounted upon the pedal support 4 as shown best in Figs. 1 and 3 is an angle bracket 10 comprising an upright arm 11 provided with a bearing 12, there being bearings 14 on the foot of the angle bracket.

Journaled for rocking movement in the bearings 14 is a shaft 15 to which is secured a pedal 16. Attached to one end of the shaft 15 is a segment 17 meshing into a beveled pinion 18 secured to an upright shaft 19 journaled in the bearing 12 and supported against downward movement by the foot of the angle bracket 10. As shown in Fig. 8, the shaft 19 may be journaled adjacent its upper end in a bearing 20 carried by one of the side braces 5. Secured to the upper end of the shaft 19 is a wheel 21. About the wheel 21 are trained in opposite directions flexible elements 22 engaged around idlers 23 carried by the table 7 or otherwise mounted, the flexible elements 22 passing upwardly through openings 24 in the table.

Fulcrumed as shown at 25 upon the front cross bar 6 of the supporting frame is a bell crank 26 embodying a vertically disposed arm 27 and a horizontally disposed arm 28. Connected with the arm 28 of the bell crank 26 is a flexible element 29, carried upwardly with respect to the table 7, as clearly shown

in Fig. 1. Fixed to and depending from the table 7 is a hanger 30 upon which is fulcrumed as shown at 31 a lever 32 with which a flexible element 33 is assembled. The flexible element 33 is carried upwardly about an idler 34 which may be mounted on the table 7 as shown most clearly in Fig. 2.

Mounted upon the pedal support 4 is an angle bracket 35 embodying an upright arm 36 provided with a bearing 37. The foot of the angle bracket 35 is equipped with bearings 38 and in these bearings is journaled for rocking movement a shaft 39 to which is secured a pedal 40. Attached to the shaft 39 is a segment 41 meshing into a beveled pinion 42 carried by a shaft 43 journaled in the bearing 37, the foot of the angle bracket 35 acting as a thrust bearing for the shaft 43, the shaft 43 being journaled adjacent its upper end in one of the side braces 5.

Noting Fig. 2 and comparing the same with Fig. 5 it will be observed that a wheel 45 is mounted to rotate on the shaft 43. Upward movement of the wheel 45 is prevented by means of a collar 46 held to the shaft 43 by means of set screws 47. Downward movement of the wheel 45 is prevented by means of a collar 48 held on the shaft 43 by means of set screws 100. Trained about the wheel 45 is a flexible element 49 carried upwardly and engaged around suitable frame supported idlers, one of which idlers, denoted by the numeral 50, is mounted to rotate on a bracket 51 upheld by the table 7, the function of the bracket 51 being to elevate the flexible element 49 sufficiently so that the same will cooperate properly with the carriage (not shown) of a typewriter.

The wheel 45 is provided with a depending rim 52^a within the contour of which is placed a removable, cone-shaped clutch shoe 52 held in place by means of a set screw 53. The clutch shoe 52 is adapted to cooperate with the cone-shaped upper end of a clutch member 54 loose on the shaft 43, the clutch member 54 being provided with a recess 55 in which the collar 48 is housed. The invention includes a resilient bracket 56, the lower end of which is attached to the table 7 or to some other accessible portion of the machine, the bracket 56 comprising, as shown in Fig. 13, diverging arms 57 provided with shafts 58 which support the rollers 59 engaged in a groove 60 formed in the periphery of the clutch member 54. The lower end face of the clutch member 54 is circumferentially inclined as shown at 61 and is provided with a shoulder 62.

A head 63 is secured to the shaft 43 by means of set screws 101, the head 63 being provided in its upper end as shown in Fig. 7 with recesses 102 in which are located wheels 103 adapted to cooperate with the inclined surface 61 of the clutch member 54, the wheels 103 being carried by shafts 104 in the

head 63. Fixed to and upstanding from the head 63 is a stop pin 105 adapted to cooperate with the shoulder 62 under circumstances which will be pointed out hereinafter.

Let it be supposed that it is desired to shift from the lower case to the capitals on a typewriter embodying a shift key adapted for this purpose. Then the heel of the pedal 16 is depressed, the shaft 15 is rotated, the same actuating the segment 17, and rotation is imparted to the shaft 19 through the medium of the beveled pinion 18. The wheel 21 is rotated and if one of the flexible elements 22 be attached to the capital shift key of a typewriter, the change from small letters to capitals will be effected. If the toe of the pedal 16 be depressed, the wheel 21 will be rotated in a direction opposite to that presupposed by the foregoing operation, and the other flexible element 22, attached to the figure shift key of the typewriter, will bring the figures of the font into position.

The lever 27 may be swung to one side by the knee of the operator, and the flexible element 29 if attached to the proper portion of a typewriter, will actuate the tabulating mechanism. The lever 32 may be swung to one side by the right knee of the operator, and the flexible element 33, if connected up with the typewriter properly, will actuate the back spacing mechanism.

In order to retract the typewriter carriage, the pedal 40 is moved, the shaft 39 being rotated and the segment 41 imparting a rotation to the shaft 43 by means of the beveled pinion 42. When the shaft 43 is rotated, the head 63 will be rotated also, the wheels 103 cooperating with the inclined surface 61 of the clutch member 54 and effecting a raising of the clutch member. When the clutch member 54 is raised in the manner above described, the cone-shaped upper end of the clutch member 54 will cooperate with the clutch shoe 52 on the wheel 45 and thus the wheel 45 is operatively connected with the shaft 43 to rotate therewith, upward movement of the wheel 45 or a rotation thereof independently of the shaft 43 being prevented by the collar 46. When the wheel 45 is rotated, the flexible element 49 will be reeled in, thus pulling over the carriage of the typewriter.

When the clutch member 54 is shifted in the manner hereinbefore described, the spring arm 56 will be put under tension. A reversed rotation of the shaft 43 will permit a lowering of the clutch member 54 by the action of the bracket or arm 56, and thus, the upper end of the clutch member 54 will be moved out of engagement with the clutch shoe 52 on the wheel 45, whereupon the typewriter carriage will move over step-by-step in the ordinary manner, the flexible element 49 being unreeled off the wheel 45 and the latter rotating freely on the shaft 43.

It will be obvious that by a proper manipulation of the pedal 40, the typewriter carriage may be pulled over throughout a limited portion only of its stroke, it thus being possible to stop the typewriter carriage at any point intermediate the ends of its retracting movement. The function of the stop pin 105 co-operating with the shoulder 62 is to prevent the wheel 45 from spinning beyond a predetermined point when the flexible element 49 is drawn off the wheel 45 by the action of the typewriter carriage.

Any suitable means may be provided for operatively connecting the flexible element 49 with the typewriter carriage. With most makes of typewriters, the connection of the flexible element 49 with the carriage may be accomplished directly. When, however, the device herein disclosed is employed in connection with an Oliver typewriter, resort is had to the construction shown in Figs. 9, 10, 11 and 12.

The left hand thumb wheel on the carriage of an Oliver typewriter is shown at 65 and the thumb wheel shaft is shown at 66. About the shaft 66 is placed a bushing 67 held in place by a set screw 68. An arm 69 is shown and the same terminates at its upper end in an eye in which the bushing 67 is received, the eye being denoted by the numeral 70. Projecting laterally from the arm 69 is an extension 71 terminally provided with an enlarged head 72 equipped with a notch 73. The notch 73 is adapted to slide 35 upon a small bar ordinarily found on the back side of the carriage of an Oliver typewriter. This sliding movement is very slight and ordinarily is of no greater extent than a quarter of an inch, this movement representing the lateral movement of the thumb wheel 65 in order to permit a spacing of the platen.

The foregoing description as above given presupposes that it is desired to use the 45 standard button or thumb wheel of an Oliver typewriter. In Figures 11 and 12 there is shown a construction in which a special thumb wheel 75 is provided, the sleeve thereof being shown at 74 and receiving the shaft

76. The sleeve 74 is held to the shaft 76 by 50 means of a cross pin 77 or in any other suitable manner. The sleeve 74 is provided with spaced annular flanges 78 between which the arm 79 is movably received. The arm 79 is offset as shown at 80 to receive the sleeve 55 74 and the offset portion 80 of the arm co-operates with a removable cap 81 held in place by securing elements 82.

Having thus described the invention, what is claimed is:—

1. In a device of the class described, a typewriter support; a pair of vertical shafts journaled on the support adjacent the sides thereof; a pair of horizontal shafts mounted to rock on the support adjacent the bottom 65 thereof; pedals carried by the horizontal shafts whereby the same may be operated selectively; angularly disposed intermeshing gear elements operatively connecting each of the horizontal shafts with one of the vertical 70 shafts; wheels assembled with the upper ends of the vertical shafts; and flexible elements carried by the wheels and adapted for connection with movable elements of a typewriter.

2. In a device of the class described, a typewriter support, a vertical shaft journaled on the support adjacent the side of the support; a pedal mounted to swing on the support; means for operatively connecting 80 the pedal with the lower end of the vertical shaft to rotate the vertical shaft; a wheel rotatable on the upper end of the vertical shaft; an automatically releasable clutch responsive to the rotation of the vertical shaft 85 and constituting a means for operatively connecting the vertical shaft with the wheel; and a flexible element assembled with the wheel, the flexible element being adapted for connection with a movable element of a typewriter.

In testimony that I claim the foregoing as my own, I have hereto affixed my signature in the presence of two witnesses.

MIZELL BENJAMIN WARD.
